(57) **CLAIM**

The ornamental design for a tubular holder, as shown and described.

DESCRIPTION

FIG. 1 is a perspective view of the tubular holder according to the present design;

FIG. 2 is an elevation side view of the tubular holder as shown in FIG. 1, the other side being a mirror image thereof;

FIG. 3 is a rear view of the tubular holder as shown in FIG. 1; FIG. 4 is an enlarged view of a closure of the tubular holder as shown in FIG. 1;

FIG. 5 is a front view of a closure of the tubular holder as shown in FIG. 1 and as seen along line 5-5 of FIG. 4;

FIG. 6 is an interior end view of a closure of the tubular holder as shown in FIG. 1 and as seen along line 6-6 of FIG. 4;

FIG. 7 is a sectional view of the tubular holder as shown in FIG. 1 and as taken along line 7-7 of FIG. 5; and,

FIG. 8 is an exploded view of a closure and opening of the tubular holder according to the present invention.

The broken lines shown in the drawings illustrate portions of the tubular holder and form no part of the claimed design.
